UNITED STATES PATENT OFFICE.

WARREN B. BURGESS, OF WASHINGTON, DISTRICT OF COLUMBIA.

RADIO RECEPTION SYSTEM.

Application filed May 14, 1923. Serial No. 638,971.

My invention relates broadly to radio reception systems, and more particularly to a circuit arrangement for reducing the effects of body capacity upon the circuits of a 5 radio compass receiving apparatus.

One of the objects of my invention is to provide means to be connected to any standard radio receiving apparatus for eliminating the capacity effect of the operator's body which normally forms with the 10 circuits of the receiving apparatus a portion of a radio frequency circuit.

Another object of the invention is to provide a system of radio frequency choke 15 coils arranged in the radio receiver circuits whereby radio frequency currents are suppressed from leads extending any substantial distance from the receiving apparatus.

Another object of the invention is to provide one or more radio frequency choke coils 20 having negligible impedance to audio frequency currents connected in the telephone circuit of the receiving apparatus whereby radio frequency currents are suppressed 25 from the telephone circuit and no effect will be produced by movement of the operator's body or the touching of any part of the receiving apparatus, and the relative position 30 of the operator's body to the apparatus will have no influence upon the functioning of the radio receiving circuits.

My invention will be more clearly understood by reference to the following specification and the accompanying drawings, in 35 which:

Figure 1 is a schematic wiring diagram of a radio receiving apparatus used in connection with a radio compass showing my invention applied to the circuits thereof;

Fig. 2 is an elemental diagram illustrating a radio compass circuit with switches arranged for cutting in or removing the radio frequency choke coils from the telephone circuit;

Fig. 3 is a theoretical characteristic curve showing the direction finder coil characteristic and the advantages produced therein when employing my invention in circuit with a radio compass receiving apparatus;

Fig. 4 is a perspective view of one form 50 which the radio frequency choke coils of my invention may take;

Fig. 5 is a cross-sectional view taken on line 5-5 of Fig. 4;

Fig. 6 is a cross-sectional view taken on line 6-6 of Fig. 4; and

Fig. 7 is a side elevation of one of the radio frequency choke coils employed in my circuit arrangement.

In radio compass receiving systems great 60 difficulty has been experienced in keeping constant the capacity to ground of the operator's body while taking a bearing. The reason for this among other things is that the telephone leads capacitatively connect 65 the operator's body into a radio frequency circuit through the receiver, his body capacity shunting that of the batteries to ground. Normally changes in this capacity must be reproduced in the compensating condenser 70 in the compass circuit to maintain the balance. In the past the only practical means employed to obviate this difficulty has been to require the operator to keep his feet on a stool away from the grounded 75 screen, and hold his body as still as possible when obtaining a balance. Touching the metal spider of the hand wheel for turning the compass or any other grounded metal, always destroyed the balance when signals 80 were loud enough to give good minima.

In the present invention I overcome this disadvantage by connecting radio frequency choke coils in one or both of the telephone leads immediately adjacent the amplifier 85 and in the battery leads in cases where they extend a substantial distance from the apparatus. The radio frequency choke coils are constructed with low impedance to the 90 audio frequency currents in the telephone circuit, and leads may be run out of the station to a line system for remote control from a distance without affecting the compass balance or the stability of the amplifier.

In the usual radio compass installation 95 the effect of movement of the operator's body is to produce erroneous observations by changing the minima signal intensity requiring a change in the compensating capacity to make an accurate observation. Unless extreme caution is exercised by the operator the observations may be a considerable percentage in error. With the provision of my radio frequency choke coils in the extended 100 leads, such as to battery leads and to telephone leads, this body capacity effect is eliminated and the operator may concentrate 105 attention upon the taking of observations regardless of his position relative to the receiving apparatus.

My invention as illustrated in Fig. 1 is 110 shown in connection with a three stage radio

frequency amplifier employing tubes 1, 2 and 3, a detector 4, and a two stage audio frequency amplifier employing electron tubes 5 and 6. The rotatable compass coil 8 is used having collector ring terminals 9 and 10 which connect with the receiving apparatus with tuning condenser 12 shunted across the loop. The A-battery 14 and B-battery 15 may be located in some installations at a substantial distance from the receiving apparatus and connected through extended leads with the filament heating circuit 16 and the plate circuit 17 of the receiver. Radio frequency choke coils 18, 19 and 20 are interposed in the several leads immediately adjacent the receiver for suppressing radio frequency currents from the leads extending to the batteries. There is an inherent capacity existing across each of the radio frequency choke coils due to the distributed capacity of the windings, and as this capacity tends to pass radio frequency currents around the chokes, I provide for a construction to reduce this distributed capacity to a minimum. If a condenser is shunted around the chokes of such capacity value when combined with the inductance of the choke to form a local circuit in resonance with radio frequency of the signal, this tuned circuit will most effectively stop the passage of the radio frequency. This is illustrated in Fig. 1 as condenser 20^a connected in shunt with choke 20. In the telephone circuit immediately adjacent the output circuit of the electron tube 6 I provide radio frequency choke coils 21 and 22. The suppression of radio frequencies from the telephone circuit permits the circuit to be extended through conductors 24, transformer or large inductance 25, switch 26, and line wire system 27 which may lead to a remote control radio compass station and deliver the telephone current at such point without deleterious capacity effects. The telephones 28 which are worn by the operator when taking observations upon incoming signals are isolated from radio frequencies, and as the operator moves to different points adjacent the apparatus no deleterious unbalancing is involved. Normally there is the inherent body capacity 29 to ground and capacity of the other parts of the circuit represented at 30. These inherent capacities normally integrate to a capacity equivalent to that represented at 31, and while one particular value may be compensated by varying condenser 32 giving the normal characteristic curve to the radio compass represented at 33 in Fig. 3, variation in the capacities 29 and 30 by movement of the operator's body is equivalent to variation of capacity 31, thereby changing the characteristic of the circuit to a curve as represented at 34, resulting in an uncertain minimum signal reading, or failure to show

a true minima. The provision of the radio frequency choke coils in my invention obviates this disadvantage as heretofore pointed out.

Fig. 2 illustrates in an elemental manner the operation of my radio frequency choke coils. In this diagram a detector tube 4 is illustrated in connection with a radio compass circuit having parts similarly numbered as in Fig. 1. In the output circuit of the tube 4 the radio frequency choke coils 21 and 22 are illustrated connected immediately adjacent the output terminals in series with the telephone cords 36 leading to the telephones 28. Shorting switches 21^b and 22^b are provided in shunt with the radio frequency chokes 21 and 22. In the operation of the radio compass with the switches 21^b and 22^b closed the compensating condenser 32 is adjusted for the best minimum, thereby balancing the antenna effect, any inherent reradiation, any unsymmetrical ground conditions, or other factors tending to obscure the null point. If now the capacity to ground through the operator's body changes, or other capacities to ground change, the null point will be obscured, as illustrated by the characteristic 34 in Fig. 3, and a new balance will have to be struck by adjustment of the compensating condenser 32. If the radio frequency choke coils 21 and 22 are put into circuit by opening switches 21^b and 22^b the inherent capacity 29 is, in effect, cut off from the radio frequency circuit and capacity changes have no effect on the balance. The chokes are maintained permanently in the circuit, their impedance to the audio frequency telephone currents being small. The radio frequency choke coils may be embodied in various constructions.

The form illustrated in Fig. 4 comprises a case 37 containing a pair of clockwise wound radio frequency choke coils 21 and 22 with their ends connected to terminals P₁ and S₁ forming the input terminals, and P₂ and S₂ forming the output terminals. The terminal posts are separated at a maximum distance apart to keep the capacity between the input and output leads to an absolute minimum to secure the best effect from the chokes. The choke coils are spaced from each other by means of the washer 38 secured in position by bolt 39 passing through bushing 40 and the side walls of the casing 37. Suitable positioning means may be passed through apertures 41 and 42 to secure the radio frequency choke coils immediately adjacent the output leads from the last stage of amplification.

While I have disclosed a particular embodiment of the radio frequency choke coils, it is to be understood that I am not limited to this particular construction and that changes may be made within the scope of

the appended claims without departing from the spirit of my invention.

Having thus described my invention, what I claim and desire to secure by Letters Patent of the United States is as follows:

1. In a radio frequency receiving system, the combination of a coil and tuning condenser, a plurality of current paths connecting said coil to earth, one of the paths consisting of a variable condenser and another of the paths comprising said tuning condenser effectively in series with ground capacity extending from portions of the system, the value of the capacity to ground being responsive to extraneous disturbances and means for rendering said value independent of the disturbances comprising a radio frequency choke coil.

2. In a receiving system, the combination with a closed circuit including inductance and tuning condenser of a plurality of current paths connecting said coil to earth, one of the paths consisting of a variable condenser and another of the paths comprising said tuning condenser effectively in series with ground capacity extending from portions of the system, the value of the capacity to ground being responsive to extraneous disturbances and means interposed between said tuning condenser and the capacity to ground for rendering the value independent of the disturbances.

3. In a direction finder, the combination of a rotatable loop having a capacity area, two current paths in parallel extending from said area to ground, one of the paths consisting of two condensers, one of which operates substantially independent of ground capacity effect and the other, being subject to momentary changes in value due to extraneous disturbances, the second path comprising a means for balancing the reactance of the first mentioned path and means, located in the first mentioned path whereby the balance is maintained and rendered independent of said disturbances.

4. In a radio frequency system, the combination with a closed circuit comprising an

inductance and a tuning condenser, of two current paths in parallel each including said inductance as a capacity area and a common capacity to ground the value of which is responsive to extraneous disturbances, one of said paths comprising in addition, said tuning condenser, whereby the reactance of the paths are unequal, means in operative relation to one of said paths for equalizing said reactances and means connected with said common capacity to ground, for rendering the latter independent of the disturbances whereby equality between reactances is preserved.

5. In a radio frequency receiving system, the combination with a closed circuit comprising an inductance and a tuning condenser, of two current paths in parallel each including said inductance as a capacity area and a common capacity to ground the value of which is responsive to extraneous disturbances, one of said paths comprising in addition, said tuning condenser, whereby the reactance of the paths are unequal, means in operative relation to one of said paths for equalizing said reactances and means connected in series with said common capacity to ground, for rendering the latter independent of the disturbances whereby equality between reactances is preserved, said means comprising a filter impassable to radio frequency.

6. In a receiving system, a closed circuit comprising an inductance coil, and a tuning condenser, said coil having a capacity area, two parallel current paths extending from said area to ground, one of said paths including the tuning condenser and a plurality of capacities, some of which are due to body capacity effects, the other path comprising an adjustable condenser for balancing purposes and means connected effectively in series with certain of said capacities for substantially eliminating said body capacity effects whereby balance is maintained.

WARREN B. BURGESS.
